UNITED STATES PATENT OFFICE.

ANITA RHODES, OF LEXINGTON, KENTUCKY.

EXTENSION TABLE.

Application filed February 25, 1922. Serial No. 539,107.

To all whom it may concern:

Be it known that I, ANITA RHODES, a citizen of the United States, residing at Lexington, in the county of Fayette and State 5 of Kentucky, have invented certain new and useful Improvements in Extension Tables, of which the following is a specification.

This invention relates to improvements in extension tables, the general object of the 10 invention being to provide means for easily and quickly varying the diameter of a circular table.

Another object of the invention is to form the table top from a number of slidable 15 members of quadrant shape and a pair of leaf members which are adapted to be placed between the quadrants when the table is to be enlarged.

This invention also consists in certain 20 other features of construction and in the combination and arrangement of the several parts, to be hereinafter fully described, illustrated in the accompanying drawings and specifically pointed out in the appended 25 claims.

In describing my invention in detail, reference will be had to the accompanying drawings wherein like characters denote like or corresponding parts throughout the 30 several views, and in which:—

Figure 1 is a plan view of the table in collapsed position.

Figure 2 is a similar view of the table in extended position.

Figure 3 is a side view of the table as shown in Figure 2.

Figure 4 is a plan view of the table with the top removed.

Figure 5 is a sectional view on line 5—5 of Figure 2.

Figure 6 is a detail perspective view of the extension members in juxtaposition.

Figure 7 is a detail of the guideways.

In these views 1 indicates the pedestal of 45 the table which is supported by the legs 2 which are provided with the casters 3. A sub-top 4 is connected with the top of the pedestal by the supporting brackets 5. This top is of square shape and has connected 50 with its upper surface the radiating bars 6, the ends of these bars projecting beyond the corners of the top. Each bar is provided with a dove-tail groove 7 in its upper face which is engaged by a similar 55 shaped tongue 8 formed on the lower face of a slidable bar 9 so that the bars 8 can

be slid longitudinally on the bars 9. A quadrant 10 is secured to each of the bars 6 and these parts are so arranged that when the bars 9 are moved inwardly the edges of 60 the quadrants will engage each other so as to form a table top of the shape shown in Figure 1. Each quadrant has a groove 10' formed in one of its straight edges and a tongue 11 on its other straight edge, the 65 tongue of one quadrant engaging the groove of the adjacent quadrant when the table is in contracted position. In order to fill up the spaces between the quadrants when they are moved outwardly to make the table of 70 larger diameter I provide a pair of leaves 12. These leaves are each provided with a groove on one side edge and a tongue on the opposite side edge for engaging the tongues and grooves of the quadrants. The 75 ends of the leaves are rounded to form with the quadrants a complete circle when the table is in extended position. The centers of the leaves intersect and are rabbeted, as at 13, so that the faces of the leaves will be 80 flush with each other and with the upper faces of the quadrants. Each leaf and each quadrant is provided with a depending apron 14 on its lower face, the ends of these 85 aprons abutting when the table is in contracted or extended condition. These aprons act to hide the sub-top and the bars and thus add to the attractive appearance of the table.

It will thus be seen that the table can be 90 easily and quickly enlarged by pulling the quadrants apart and placing the two leaves in position and then closing the quadrants until their tongue and grooved edges engage the tongue and grooved edges of the leaves. In this position of the table its top 95 will form a complete circle. When a smaller table is desired it is simply necessary to remove two leaves and move the quadrants inwardly until the edges engage. 100 This will make the top a distorted circle.

It is thought from the foregoing description that the advantages and novel features of my invention will be readily apparent.

I desire it to be understood that I may 105 make changes in the construction and in the combination and arrangement of the several parts, provided that such changes fall within the scope of the appended claims.

What I claim is:—

1. A table of the class described comprising a pedestal, a rectangular sub-top secured

thereto; brackets secured to the pedestal and supporting the sub-top, radial guide bars secured to the sub-top and extending over and beyond the corners thereof, slidable bars having tongue and groove connections with the guide bars, a quadrant-shaped top part connected with each slidable bar, said quadrants having tongue and groove connections with each other, a pair of removable leaves for occupying the space between the quadrants, the centers of said leaves intersecting each other and said centers being rabbeted, and aprons secured beneath the quadrant-shaped top and removable leaves.

15 2. A table of the character set forth com-

prising rightangularly disposed bars extending outwardly from the center of the table, a rectangular sub-top having its sides obliquely disposed between the bars and its corners lying on planes in vertical alignment with lines passing through the centers of the bars, means securing the bars to the sub-top, quadrant-shaped leaves slidably engaged with the bars, and intermediate leaves between the quadrant-shaped leaves, said leaves lying on planes midway between the bars.

In testimony whereof I affix my signature.

ANITA RHODES.
